DESIGN FOR A RUG

Lucien Biva, Long Island City, N. Y., assignor to William E. Roschen, Spring Lake, N. J., and John Hastedt, Teaneck, N. J., as coexecutors of the estate of Otto Timme, deceased, doing business as E. F. Timme & Son, New York, N. Y.

Application October 28, 1941, Serial No. 103,922

Term of patent 7 years

To all whom it may concern:

Be it known that I, Lucien Biva, a citizen of the United States, and a resident of the city of New York (Long Island City, Borough of Queens), county of Queens, and State of New York, have invented the new, original, and ornamental Design for a Rug, of which the following is a specification, reference being had to the accompanying drawing, forming part thereof.

The figure is a plan view of a rug embodying my design.

I claim:

The ornamental design for a rug, as shown.
LUCIEN BIVA.
